UNITED STATES PATENT OFFICE

2,038,231

CENTRIFUGAL RING-GRINDING MILL

John J. Moisan, San Francisco, Calif., assignor of
one-fourth to George M. Icard, San Francisco,
Calif.

Application March 13, 1933, Serial No. 660,530

4 Claims. (Cl. 83—9)

The present invention relates generally to improvements in centrifugal ring-grinding mills, and especially to mills adapted to both wet and dry crushing of ore, rock, or any crushable material 5 that is to be reduced to any predetermined degree of fineness.

It is the primary object of the present invention to provide an efficient, non-clogging, and high velocity mill that has greater reduced wearing 10 surface areas than the mills now in general use.

Another object of the invention is to provide a centrifugal ring-grinding mill of the class described, that is sufficiently light in construction and adapted to carry either the wet or dry crushing process; and enabling the users of said mill to operate the same with greatly reduced motive power.

A further object of the invention is the provision of a mill including self-cleaning screening 20 grids mounted in such a manner as to permit their ready and uniform adjustment for the increasing or decreasing of the width of the passages between said grids at the will of the operator of said mill.

25 A further object of the invention is the provision of a centrifugal ring-grinding mill of the class described, which embodies a classifier adapted to sort the material that has been crushed by said mill, said classifier being equipped with grids 30 of a similar nature to those used in said mill and operated and controlled in a slightly modified manner.

35 A further object of the invention is the provision of a mill of the class described, which embodies means for returning oversize material from the classifier to the mill for regrinding, or for removal of said material from the classifier at a point adjacent to the top of said mill.

40 A still further object of the invention is to provide a mill of the class described, which embodies means for normally causing the crushable material to be forced through the mill without employing any additional screw conveyor, hydraulic force, or blower.

45 A further important object of the invention is to provide a mill which is so constructed that a number of nests or groups of annuli may be used in proportion to the hardness of the material to be crushed.

50 A still further important object of the invention is to provide a mill which is so constructed as to permit its being shipped in small sections to remote locations without weakening or loss of any of the mill's salient features, also to provide for the ready inspection and replacement of the in-

ternal parts subject to wear or operating damage.

In the accompanying drawings:—

Figure 1 is a longitudinal sectional elevation of the mill illustrating the shell and lining thereof, the feed and discharge hoppers, frame spacers, 5 frame spacer rings, a plurality of annuli, internal locking rings for adjusting the screening grids, rubber shock and guide rings, also the classifier, adjustable scoop, return launder mechanism, sealed dust and splash housing, and standard for 10 holding said housing, also means for mounting and driving said mill;

Figure 2 is a transverse section taken on the line 2—2 of Figure 1, and illustrating the location of the grinding annuli, millers, screening grids, 15 shell lining, and internal rings for adjusting the screening grids;

Figure 3 is an enlarged sectional detail taken on the line 3—3 of Figure 2, and illustrating the method used in mounting the screening grids, and 20 the means for adjusting the size of the passages between the triangular bars;

Figure 4 is a vertical sectional detail taken on the line 4—4 of Figure 3 depicting means for retaining and removing the triangular bars; 25

Figure 5 is a top plan view of the removable segments forming bearing caps for the triangular bars;

Figure 6 is a reduced plan view of the castellated 30 internal locking rings to permit the insertion of the bar-spacer and locking members shown in Figures 3 and 4;

Figure 7 is a transverse section of the castellated internal locking rings, whose flanges contact on 35 their inner faces the frame spacer rings of the mill;

Figure 8 is a transverse section of the classifier taken on the line 8—8 of Figure 1, illustrating the screening grid, locking ring, adjustable scoop, 40 return launder, stay bolts and pipe spacers, also showing the fine ground material passing through the passages between the triangular bars to the discharge hopper, and the coarser material being lifted up by centrifugal force to the adjustable 45 scoop and return launder;

Figure 9 is a greatly enlarged fragmentary section of Figure 8, depicting in greater detail the method employed in mounting the locking ring, triangular bars, stay bolts and pipe spacers, and bearing caps for the triangular bars; 50

Figure 10 is a vertical section taken on the line 10—10 of Figure 9, illustrating the means of retaining the triangular bars;

Figure 11 is a top plan view of a typical bear- 55

ing cap as applied to the triangular bars mounted in the classifier head of said mill; and

Figure 12 is an enlarged perspective view of a triangular bar, as applied to my invention.

- 5 In the description of the preferred form of my invention, as disclosed in the drawings, the various mechanisms include broadly, a cylindrical shell 13; feed hopper 14; frame spacers 15; grinding annulus nests 16; screening grids 17; classifier 18; adjustable scoop and return launder mechanism 19; mill support rollers 20; and motive power attachment 21.

The mill comprises, specifically, the cylindrical shell 13 consisting of a metallic cylinder 22 upon whose opposite ends are mounted the flanged members 23 and 24, and the mill tires 25 and 26, all clearly shown in Figure 1.

The cylindrical shell 13 is provided with a plurality of ringlike linings 27 which are provided with various segments 28, 29, 30, 31, 32, and 33, to facilitate their installation, as shown in Figure 2, the end faces 34 and 35 of said segments being tapered to permit positive gripping of the frame spacers 15, whose detail parts will be hereinafter more fully described.

The feed hopper 14 consists of a truncated cone shaped exterior shell 36 provided with a suitable opening 37 permitting the entry of the mill charge, said feed hopper 14 being fitted with a similarly formed metallic liner 38 which may be replaced when it becomes worn. The feed hopper 14 is securely fastened by means of bolts 39 to the flanged section 23 of the cylindrical shell 13, as disclosed in Figure 1.

35 The frame spacers 15 are composed of a plurality of plates 40, so shaped as to fit snugly against the countersunk outer rings 41 abutting the cylinder 22, said outer rings being provided with a plurality of cap screws 42 securely holding the outer rings 41 and plates 40 in rigid alignment. The internal faces of said outer rings 41 are equipped with replaceable wearing plates 43.

40 Radially arranged about the center of the mill and projecting from plates 40 are a plurality of studs 45 containing inner spacer rings 46 and the screening grids 17, as shown in Figures 2 and 3, said inner frame spacer rings 46 have their opposite faces deeply grooved and having cemented therein rubber shock and guide rings 50 47, as depicted in Figures 1, 2, 3, and 4.

In the grinding compartments 48, 49, 50, 51, and 52, are mounted a group of grinding annulus nests 16 consisting of a plurality of members 53, 54, and 55, of varying diameters. Inserted in the innermost part of each said nest is a muller 56. Each of said grinding nests 16 is free to shift about within its respective grinding compartment irrespective of the action being taken by any of the other nests due to the 55 rotation of the mill. The inner and outer peripheries of the grinding annuli 53, 54, and 55, and the outer faces of the muller 56 function as the active grinding and crushing agents of the device.

60 65 Mounted between the plates 40 are the screening grids 17, comprising triangular bars 57, and bar-spacer and locking members 58, said bar-spacer and locking members being slidably mounted on a plurality of cap screws 59 passing through the slots 60 and secured to the inner frame spacer rings 46, as shown in Figures 3 and 4.

The triangular bars 57 are provided with dowels 61 and 62 which function as pivots for said bars to permit their rotation, as shown in Figure 5.

ures 3 and 12. The inner frame spacer rings 46 are recessed and form half bearings 63 to provide for the insertion of the dowels 61, Figures 3 and 4, and bearing caps 64 are securely fastened with cap screws 65 to said inner frame 5 spacer rings 46. The bearing caps 64 are provided with bearing grooves 66, said grooves functioning as the outer half of the bearing surfaces for the dowels 61 and the drilled holes 67, as depicted in Figure 5, functioning as the gripping 10 medium for the cap screws 65.

The plates 43 of the frame spacers 15 are provided with a plurality of drilled holes 44 to receive the dowels 62 of the triangular bars 57 and with said holes acting as bearings for said triangular bars 57, as disclosed in Figure 2.

The bar-spacer and locking members 58 are so shaped that they contact the triangular bars 57 upon two faces, thus preventing any movement from the desired position predetermined 20 by the operator of the device. Shifted or changed positions of the triangular bars 57 are indicated by dot-and-dash lines in Figure 3.

The castellated rings 68 function as the shifting and locking devices for the various groups of 25 screening grids 17, and said rings are fabricated from flanged members with the castellations 69 therein, permitting insertion of the bar-spacer and locking members 58, as disclosed in Figures 2, 3, 4, and 6. Drilled holes 70, 71, and 72 are 30 provided in said castellated rings 68 for obtaining any desired setting of the screening grids, namely—fine, medium, and coarse. The movement of the screening grids in any given direction will either increase or decrease the 35 passages between the triangular bars 57, thus limiting the size of the material that may be passed between the triangular bars 57 of said screening grids. The flanged portions 73 of said castellated rings 68 abut the opposite ends of the bar-spacer and locking members 58 at the points indicated by the numerals 74 and 74'. The inserted bolts 75, Figure 2, are removed from the frame spacer rings 46 when it is desired to shift 40 the position of said castellated rings.

The classifier 18 is composed of inner and outer ring frames 76 and 77, stay bolts 78, and pipe thimbles 79, said pipe thimbles holding said inner and outer ring frames in spaced relation without causing any undue pressure to be applied 50 to the triangular bars 57'. The triangular bars 57' perform a similar screening operation in both the classifier and in the screening grids between the various grinding compartments, and are therefore of identical construction. The inner 55 ring frame 76 is rigidly held against the flanged members 24 and abuts the end of the cylindrical shell 13, and is held rigidly in place by means of cap screws 80.

The locking ring 81, as disclosed in Figures 1, 8, 9, and 10 is provided with annularly arranged slots 82, position adjusting perforations 83, 84, and 85, and is of like arrangement to the drilled holes 70, 71, and 72 of the castellated ring 68; and also includes triangular bar gripping means similar in form to those provided in the bar-spacer and locking members 58 of the screening grids 17. Bolts 84', Figures 8, 9, and 10, inserted in the locking ring 81 are removed when it is desired to 70 shift said ring to a different position in order to change the grade of the classifier's output.

The annularly arranged slots 82 are provided to permit the ready adjustment of the locking ring 81 without disturbing the tension on the 75

stay bolts 78 and pipe thimbles 79, as clearly disclosed in Figures 8 and 9.

The outer ring frame 77 is recessed to form half bearings 86 for receiving the dowels 61' of the triangular bars 57', Figures 9 and 10, and the internal bearing caps 87 are securely fastened by the countersunk screws 88 to said outer ring frame 77. The bearing caps 87 are so shaped as to conform with the inner face of the outer ring frame 77, as disclosed in Figures 9 and 11, and are provided with a plurality of bearing surfaces 89, forming the inner half of the bearings for the dowels 61'. The countersunk holes depicted in Figure 11 are provided for, and function as the gripping medium for the countersunk screws 88. The inner ring frame 76 is provided with a plurality of drilled holes 76' to receive the dowels 62' of the triangular bars 57', and said holes functioning as bearings for said triangular bars 57', as disclosed in Figure 1.

The classifier 18 is equipped with a dust and splash housing 90 supported by the upright standard 91, and provided with an opening 92 permitting the desired adjustment of the scoop and return launder mechanism 19. The dust and splash housing 90 is also provided with a rubber sealing ring 93 contacting the mill tire 26, as depicted in Figure 1 of the drawings, and said ring prevents dust particles of the refined material from becoming entrapped upon the working surface of the mill tire 26; thus eliminating the uneven rotation of the device. A discharge hopper 94 of truncated cone shape is provided at a suitable point in the lower part of the dust and splash housing 90, and is equipped with an ejection port 95, Figures 1 and 8 of the drawings.

The adjustable scoop and return launder mechanism 19 comprises, a telescopic scoop lip 96, discharge body casting 97, and adjusting lock bolt 40 and nuts 98, said lock bolt and nuts being securely fitted into the lugs 99, all clearly shown in Figures 1 and 8. The discharge body casting 97 is rigidly mounted upon a slidable and rotatable axis 100, and said axis is provided with inner and outer U-clamps 101 and 102, with said clamps firmly gripping the upright standard 91. When the U-clamps 101 and 102 are loosened, the axis 100 may be shifted to any desired position as indicated by the double directional arrows shown in Figures 1 and 8. The return launder fitting 103 whose transverse section is substantially of U-shape, is mounted directly beneath the discharge body casting 97, and said return launder fitting 103 is rigidly mounted upon a 55 slidable axis 104 securely fastened by means of inner and outer U-clamps 105 and 106, to the upright standard 91. The return launder fitting 103 may be moved by the operator of the device in accordance to the position taken by the members 53 and 54 of the grinding annuli in the grinding compartment 52. Should the operator of the device desire to remove entirely the material caught by the adjustable scoop and return launder mechanism 19, he disconnects the return launder fitting 103 and substitutes a material transfer trough (not shown), thus disposing of 60 said material in any desired manner.

The mill support rollers 20 consist of suitable wheels 107, meshing frictionally, with the mill tires 25 and 26, all clearly disclosed in Figure 1, said wheels 107 being press-fitted to shafting 108 and operating through bearings 109, which bearings are mounted upon adequate foundations 110.

The mill, as disclosed in the drawings, is driven 75 by the motive power attachment 21 consisting of

a pulley 111 securely fastened to the cylindrical shell 13 of the mill. The rubber belt 112 transmits the necessary power to rotate the mill from any convenient source not disclosed in the drawings.

Following a period of continuous operation the grind-members 53, 54, and 55 become worn to such an extent that their operation is no longer efficient, said members should then be removed from the mill and if any two of the above mentioned members will telescope together, they may be welded into a single unit and again used in the mill.

In recapitulation:—

The crushable material in being treated in the mill, passes from the feed hopper 14 through a series of screening grids 17 in the direction indicated by the arrows in Figures 1 and 3 and into the first grinding compartment 48, where the action of the annulus nest 16 performs the first or coarsest grinding. The crushed material is now passed through the screening grids 17 into the next compartment 49 where said material is again subjected to grinding. A like operation is performed in each succeeding compartment until the now refined material drops into the classifier 18. The classifier 18 being securely fastened to the body of the mill, is therefore constantly rotating and screens the refined material as it is received from the final grinding compartment 52. This rotation causes the fine particles of the refined material to pass between the triangular bars 57' into the discharge hopper 94 and thence out through the port 95, as indicated by directional arrows in Figures 1 and 8. The remaining large material is now elevated by centrifugal force and is caught by the adjustable scoop and return launder mechanism 19, as depicted in Figure 8, and is either returned to the mill for more grinding or is withdrawn from the classifier by means of a material transfer trough. Should the operator of the mill desire to screen the material that has been refined to such a degree of fineness that it is impossible to further reduce the passages between the triangular bars 57' to the desired width, the operator partly collapses the telescopic scoop lip 96. The added clearance between the triangular bars 57' and the telescopic scoop lip 96 permits the large material to continue around the mill, forming a filter bed through which only extremely fine material can be passed. The readjustment of the telescopic lip 96 to its original setting promptly removes this filter bed and the mill is free to operate as originally intended.

Should it be desired to treat the crushable material in a bone-dry manner, it has been found that the triangular bars 57 and 57', being mounted in substantially blower-vane positions, do create enough draft suction when the device is rotated, to cause the material charge to be pulled rapidly through the mill, and thus greatly increasing the operating efficiency of the device.

Having thus described my invention and with intent not to be limited to or by details of construction of the particular disclosure embodied in the drawings or hereinbefore described.

I claim and desire to secure by Letters Patent of the United States the following:—

1. In a centrifugal ring-grinding mill of the class described, in combination, a classifier associated therewith, said classifier embodying a plurality of angularly faced grids, means for rotatably mounting said grids, and ring means associated therewith for changing the angular posi-

tions thereof to increase and decrease the passages therebetween.

2. In a centrifugal ring-grinding mill of the class described, including a classifier embodying a plurality of screening grids, said grids arranged in concentric relation to the axis of rotation of the classifier, said grids being mounted for independent axial rotation, and a ring cooperating therewith, to retain the same in fixed positions, and also including means for the adjustment of same relative to each other.
3. In a centrifugal ring-grinding mill of the class described comprising, cylindrical means for containing and rotating a body of ore to be pulverized, means for propelling the material thru said mill consisting of a plurality of radially arranged groups of triangularly formed members,

ring means for adjusting said groups to limit the passage of ore therebetween whereby the ore is ground to a predetermined degree of fineness.

4. In a device of the class described comprising a rotatable shell adapted to contain a body of material to be ground, a plurality of grinding compartments arranged therein, grinding annuli in said compartments, said grinding annuli consisting of a plurality of nested rings arranged in the various compartments, and sorting and distributing means adapted to propel the material from compartment to compartment comprising, triangular elements arranged between each compartment, and means for adjusting said triangular elements.

JOHN J. MOISAN.
